Application June 24, 1936, Serial No. 87,020

9 Claims. (Cl. 19—75)

This invention relates to new and useful improvements in separators.

One object of the invention is to provide an improved cotton separator which will efficiently drop the cotton from the air stream which draws the cotton from the wagon, or other source.

An important object of the invention is to provide an improved cotton separator which is so constructed that a continuous suction or pull may be effected, which makes for more efficient feeding of the cotton into the separator.

An important object of the invention is to provide an improved cotton separator wherein a portion of the separating screen extends over the inlet, with means for wiping the entire surface of the screen, whereby upon the introduction of the cotton into the separator, the air is immediately separated therefrom and passes upwardly through said screen.

Still another object of the invention is to provide a cotton separator having an open reel therein, whereby substantially no obstruction to the cotton introduced into the separator is had, which permits the cotton to quickly fall downwardly within said separator by gravity.

A further object of the invention is to provide an improved separator wherein the incoming cotton is dropped into a dead air space, and means for removing the cotton from this space, whereby the cotton emitting from the separator is entirely free of air.

Still another object of the invention is to provide a separator having a comparatively coarse screen therein, with means for constantly keeping the entire surface of said screen clean, whereby the air may readily pass therethrough and also whereby particles of dirt, or other extraneous matter may also be separated from the cotton.

A particular object of the invention is to provide an improved cotton separator having a flared inlet, whereby choking of said inlet is obviated and also whereby the incoming cotton may expand to open up said cotton and separate the locks thereof, which greatly improves the condition of the same.

A still further object of the invention is to provide an improved vacuum paddle wheel for a cotton separator which is simple and sturdy in construction, and which is arranged so that its flexible blades may be readily replaced without removing the wheel from the separator.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a perspective view of a separator, constructed in accordance with the invention,

Figure 2 is a similar view, having an end wall removed,

Figure 3 is a transverse, vertical sectional view of the same,

Figure 4 is an enlarged, partial vertical, sectional view of the vacuum wheel,

Figure 5 is a front elevation of the same, and having a portion of the casing broken away, and

Figure 6 is an enlarged partial perspective of the paddle wheel.

In the drawings, the numeral 10 designates an air-tight casing or housing which is preferably constructed of sheet metal, or other suitable material. An enlarged air conduit 11 is connected to the lower end of the rear wall of the housing and communicates with the interior thereof. The conduit is preferably disposed at an angle so that a free passage of air from the housing into said conduit may be had. A suitable cotton suction fan (not shown) is located in the other end of the conduit 11 and thus, it will be seen that said fan will draw an unobstructed stream of air from the housing into the conduit.

The front wall of the casing or housing extends forwardly and converges toward the central portion of said housing, whereby a reduced cotton inlet 13 is provided at the extreme forward end of the housing. It is pointed out that this inlet 13 extends transversely throughout the length of the housing. A suitable transition 14 is connected with the inlet 13, and this transition communicates with a conductor (not shown) leading to the wagon or other source of cotton supply. It is obvious that when the suction means at the end of the conduit 11 is operating, cotton is drawn through the transition 14, inlet 13 and into the housing 10. The suction means exerts an undiminished, continuous pull on the cotton within the transition 14 due to the location of the inlet 13 centrally of the housing and also due to the particular disposition of the conduit 11, whereby an even flow of cotton into the housing is had.

The lower end of the housing is provided with a transverse opening 15 which extends the full length thereof and a suitable discharge spout 16 which has a general circular shape in cross-section, is connected to the discharge opening. A vacuum paddle wheel 17 is rotatably mounted

within the discharge spout and is so constructed as to prevent the escape of air through the discharge spout while permitting the discharge of cotton from the housing 10. The details of the 5 paddle wheel will be hereinafter described. A suitable outlet conductor 18 is connected to the lower end of the spout 16.

For preventing the cotton which is drawn into the housing 10 through the inlet 13 from escaping 10 through the air conduit 11, and also for directing such cotton to the discharge spout 16, a curved metal sheet 18 is located within the housing. This sheet is suitably secured to supporting members 19 which are fastened to the rear and upper 15 wall of the housing. The supporting members 19 not only hold the sheet 18 in position within the housing but also serve to space said sheet from the rear wall thereof, whereby an air space or 20 passage 20 is provided between said sheet and the rear wall of the housing. As is clearly shown in Figure 3, the sheet 18 extends from the upper end of the inclined front wall of the housing and curves rearwardly and downwardly in front of the open end of the air conduit 11. The sheet is 25 provided with a plurality of perforations or openings 21 which extend from its extreme upper end down to a point at some distance from the lower end thereof. In other words, the perforations terminate short of the lower edge of the sheet, 30 whereby a solid baffle 22 is formed by this unperforated lower end of the sheet. As is clearly shown in Figure 2, the solid portion or baffle 22 of the sheet extends transversely the entire length of said sheet and is located just above the discharge opening or outlet 15 of the housing.

As cotton is drawn into the housing through the transition 14 and inlet 13 by the suction created in the conduit 11, it will be seen that said cotton will first strike the flared front wall 40 of said housing. The wide angle formed by the converging front wall provides ample space for expansion of the incoming cotton and immediately a portion of this incoming cotton will drop downwardly through the discharge opening 15 45 in the housing. Also, this increased expansion space prevents the cotton from crowding against the top of the housing and thereby, prevents any choking effect at the inlet. The cotton which does not drop immediately upon its introduction 50 into the housing 10 will, of course, be drawn with the air stream against the perforated sheet 18 and will follow the contour of said sheet until it finally passes out to the opening 15 into the discharge spout 16. The air upon entering the inlet 55 13 will, of course, immediately rise and pass through the perforations in the forward end of the sheet 18 which overlies a portion of the flared forward end of the housing.

It is noted that the perforations 21 of the sheet 60 are comparatively large, whereby dirt and other extraneous matter is drawn through the perforations. Due to the baffle 22 at the lower end of the sheet, it is obvious that the air must follow the contour of the housing since it cannot pass directly in a straight line from the inlet 13 to the conduit 11. By directing the air in this manner, it is obvious that a circulation is set up within the housing.

For wiping the perforated sheet 18 so as to 70 keep the perforations 21 open, whereby the passage of air therethrough is not interfered with, a rotatable wheel 23 is located within the housing 10. The reel includes a plurality of spiders 24 mounted on a transverse shaft 25 which has its 75 ends suitably supported in the end walls of the

housing. The shaft is preferably in horizontal alignment with the inlet opening 13. Each spider is provided with a plurality of radially extending arms 26 which have transverse flexible wipers 27 5 suitably secured thereto. The curvature of the 10 perforated sheet 18 at its upper end is substantially the same as the radius of the arms of the spiders, whereby when the reel 23 is rotated the flexible wipers 27 will engage the surface of the sheet to clean the same. It is noted that the construction of the reel in this manner provides an 15 open structure, whereby the passage of air through the housing is not interfered with by the rotation of the reel. This eliminates an intermittent pulsating effect on the suction because the 20 usual solid paddle wheel is replaced by the open reel 23. Also, the open structure does not interfere with the falling cotton within the housing. It is further pointed out that the curvature of the 25 perforated sheet 18 is such that the entire portion 20 of said sheet is wiped or cleaned by the reel and thus, since the screen is kept clean, the suction is stronger because there is less tendency of the screen to clog.

From the above, it will be seen that the cotton 25 is drawn into the housing through the inlet 13 and immediately enters the flared front portion of said housing wherein it is permitted to expand. Due to the inlet being located centrally of the flared front portion, it is obvious that the air will 30 immediately rise in the housing while the cotton will drop down. The rising air will, of course, pass through the perforated screen and then follow the curvature of the housing, passing outwardly through the conduit 11. All dust and dirt 35 of a fine nature will pass with the air through the perforations in the sheet and will thus be separated from the cotton. The cotton upon entering will, of course, immediately expand and then fall into the discharge spout 16. The expansion of the cotton will cause the cotton to be 40 separated whereby any solid wads which may have been formed in the cotton previous to its inlet, are broken up. Thus, the cotton is opened up and the locks separated to a great extent, 45 whereby the cotton is in a good condition to be handled through the distributor or cleaning machinery (not shown) to which it is carried after it leaves the housing. The open reel not only 50 offers no obstruction to the falling cotton but also permits air to freely flow therethrough and thus does not interrupt the suction necessary for drawing the cotton into the housing.

As the air is separated from the cotton, said cotton will drop downwardly through the outlet 55 opening 15 in the bottom of the housing and will fall into the discharge spout 16. Upon entering the spout 16, the paddle wheel 17 therein will carry the cotton downwardly and discharge it into the outlet conductor 18. The paddle wheel 60 17 may be of any desired construction but it is preferably made of a plurality of supporting spiders 30 which are secured on a transverse shaft 31 extending the full length of the discharge spout 16. The spiders are provided with radial 65 arms 31 and the space between the spiders is closed by a transverse substantially V-shaped partition 32 which is located between the arms of the spider (Figure 6). These partitions are 70 suitably bolted in place by retaining members 33 which follow the contour of said partitions and the spider arms. As is clearly shown in Figure 6, the outer edges of the partitions 32 extend beyond the end of the arms 31 of the spiders and flexible wipers 34 are secured or clamped between 75

these extended outer edges of the partitions. It is obvious that as the paddle wheel thus formed rotates within the discharge spout 16 the flexible wipers 34 will contact the inner surface of the discharge spout and will thus prevent the escape of any air through said spout. At the same time the cotton dropping from the housing 10 will drop upon the substantially V-shaped partition 32 located between the spider arms 31 and will thus 10 be carried around by the rotating wheel and discharged into the outlet conductor 18.

Although the reel 23 in the housing 10 and the reel 17 within the discharge spout 16 may rotate at any desired speed, it is preferable that the reel 15 rotate at a comparatively slow speed while the paddle wheel 17 which has a much smaller diameter rotates at a greater speed. For transmitting motion to the reel 23 and the paddle wheel 17, the shaft 25 of said reel has one end extended 20 outwardly through the end wall of the housing 10 (Figure 1). The extreme outer end of this shaft carries an enlarged gear 35 and this gear is connected through a chain 36 with a small gear 37 which is mounted on the extended end of the 25 shaft 31 of the paddle wheel. A motor, or any other suitable means, may be connected to either one of the shafts to rotate the same, but I have shown a drive wheel 38 mounted on the paddle wheel shaft 31. A belt is arranged to pass over 30 this drive wheel to impart rotation to said shaft. It is clear that when the paddle wheel 17 is rotated at a given speed, the reel 23 will be rotated at a much slower speed due to the connection between the small and large gears 37 and 35 respectively, by the chain 36.

The operation of the device is obvious. The suction means (not shown) at the end of the conduit 11 will draw the cotton from the transition 40 13. Upon entering the housing the cotton is permitted to expand due to the wide angle of the front portion of the housing. The air will immediately tend to rise within said housing while the cotton will drop toward the discharge spout 16. The open reel 23 will not interfere with the falling cotton or with the air stream whereby an undiminished continuous pull on the cotton is had. The air will, of course, escape through the perforations in the sheet 18 and will 45 carry any fine dust or dirt therewith. As the cotton falls toward the discharge opening 15 it will be seen that it will fall opposite the baffle 22 formed by the unperforated section of the sheet 18. This baffle causes the air to pass upwardly 50 therearound into the conduit 11 and thus creates a dead air space at a point just above the discharge opening 15. The revolving vacuum paddle wheel 17 removes the cotton out of the air below the sheet. The structure of the paddle wheel prevents any escape of air through the discharge and thus only cotton alone is carried to the outlet conductor 18. Due to the wide internal angle adjacent the inlet 13, it is practically impossible to feed sufficient cotton through a 55 standard telescope to choke the separator down by overfeeding the suction. It is obvious that the vacuum feeder can be speeded up to suit the particular installation. It is again noted that this type of cleaner is a great improvement in the 60 preparation of the cotton for ginning. Instead of being dropped in solid wads as tramped in the cotton wagon, or other source of supply, the cotton is opened up and the locks separated to a much greater expanse, so that the cotton is in good condition to be handled through the distributor or 65

cleaning machinery. A hinged panel 10' may be provided in the front wall of the housing 10 so that the interior of the housing may be readily accessible. It is noted that the wiper 27 on the reel as well as the wiper 34 on the paddle wheel 5 17 may be readily replaced without removing the reel 23 or wheel from the device.

What I claim and desire to secure by Letters Patent is:

1. A cotton separator including, a housing having an outwardly extending convergent wall and having an inlet opening in its reduced end, a suction conduit connected in its opposite wall for drawing the cotton into the housing through the inlet opening, a screen within the housing open 15 to said inlet for separating the cotton from the air stream, said screen having a portion thereof extending from and underlying the convergent wall of the housing, means within the screen for cleaning the entire surface of the screen, and a 20 discharge in the bottom of the housing for the cotton therein.

2. A cotton separator including, a housing having an outwardly extending convergent wall and having an inlet opening in its reduced end, a suction conduit connected in its opposite wall for drawing the cotton into the housing through the inlet opening, a screen within the housing for separating the cotton from the air stream, said screen having a portion thereof within the convergent wall of the housing, an open structure 25 reel within the housing for cleaning the entire surface of the screen without interrupting the air stream therethrough and without interfering with the cotton, and means for discharging the 30 cotton from the housing separately of the air.

3. A cotton separator including, a housing having an outwardly extending convergent wall and having an inlet opening in its reduced end, a suction conduit connected in its opposite wall 40 for drawing the cotton into the housing through the inlet opening, a coarse curved screen within the housing for separating the cotton from the air and fine dust, said screen having a portion thereof within the convergent wall of the housing, and means for discharging the cotton from 45 the housing separately of the air.

4. A cotton separator including, a housing having an outwardly extending convergent wall and having an inlet opening in its reduced end, 50 a suction conduit connected in its opposite wall for drawing the cotton into the housing through the inlet opening, a coarse curved screen extending from and underlying the convergent wall of the housing for separating the cotton from the 55 air and fine dust, said screen having a portion thereof within the convergent wall of the housing, a rotatable open structure reel within the screen for cleaning the entire surface of the screen, and means for discharging the cotton 60 from the housing separately of the air.

5. A cotton separator including, a housing having a divergent inlet, a stationary arcuate screen extending from the divergent top wall of the housing to the bottom of said housing and 65 dividing the housing into a cleaning chamber and an air chamber, and a revolving cleaner operating on the inner surface of the screen for wiping the same.

6. A cotton separator including, a housing 70 having a divergent inlet, a stationary arcuate screen extending from the divergent top wall of the housing to the bottom of said housing and dividing the housing into a cleaning chamber and an air chamber, a revolving cleaner 75

operating on the inner surface of the screen for wiping the same, and means at the lower end of the cleaning chamber of the housing for receiving cotton therefrom and for discharging said cotton separately from the air.

5 7. A cotton separator including, a housing having a cotton inlet at approximately mid-height of one side wall thereof, a suction conduit connected to the opposite wall of said housing 10 for drawing cotton into the housing and across the same through the said inlet, a stationary upright screen mounted within the housing between the inlet and the conduit for arresting the passage of the cotton and separating the 15 same from the air stream, and a revolving wiper within the housing between the inlet and the screen constantly wiping the entire inner surface of said screen to maintain said screen surface free of the accumulation of cotton and to produce an unobstructed passage for the air.

20 8. A cotton separator including, a housing having an inwardly flared cotton inlet along one side, a suction conduit connected in the opposite side of the housing below said inlet for drawing cotton into said housing through said inlet and across said housing, an upright stationary screen within the housing between the inlet and the conduit thereof and open to said inlet and receiving cotton therefrom for separating the 25 30 latter from the air stream, means within the housing between the screen and the inlet for

cleaning the screen, whereby the entire surface of the screen is maintained free of cotton and unobstructive to the passage of air therethrough, a discharge spout for the cotton below the screen, said screen and the inlet side of the housing 5 discharging into said spout, and means within the spout for discharging cotton received from the screen and housing without permitting the escape of air from the housing.

9. A cotton separator including, a housing 10 having an inwardly flared cotton inlet at one side, a suction conduit connected in the opposite side of the housing for drawing cotton from the inlet across said housing, an upright stationary screen within the housing between the inlet and 15 suction conduit and open to said inlet for receiving cotton therefrom and separating the latter from the air stream, a cleaning reel within the housing between the screen and the inlet for cleaning the screen without interrupting the air 20 stream, whereby the entire surface of the screen is maintained free of cotton and unobstructive to the passage of air therethrough, a discharge spout connected with the screen and the inlet side of the housing, whereby cotton flowing down 25 the stream is discharged into the spout, and means within the spout for discharging the cotton therefrom without permitting the escape of air from the housing.

30 BRONSON C. WOODFORD.
